United States Patent Office

Des. 222,888
Patented Jan. 25, 1972

222,888

DRESSER

Oscar Lax, South Orange, N.J., assignor to The Bennington Company, Union, N.J.

Filed Apr. 17, 1970, Ser. No. 22,488

Term of patent 7 years

Int. Cl. D6—04

U.S. Cl. D33—6

Fig. 1

Fig. 2

FIG. 1 is a front view of a dresser showing my new design.

FIG. 2 is a side view.

The side not shown is a mirror image of the side shown while the top and back are conventionally flat and unornamented.

I claim:

The ornamental design for a dresser, as shown and described.
